McCORMACK C. McPHERSON

THERMOSTATIC CIRCUIT CLOSER

Filed Aug. 21, 1922

UNITED STATES PATENT OFFICE.

McCORMACK C. McPHERSON, OF HAMMOND, INDIANA.

THERMOSTATIC CIRCUIT CLOSER.

Application filed August 12, 1922. Serial No. 581,448.

To all whom it may concern:

Be it known that McCORMACK C. McPHERSON, citizen of the United States, residing at Hammond, in the county of Lake 5 and State of Indiana, has invented certain new and useful Improvements in Thermostatic Circuit Closers, of which the following is a specification.

The present invention relates to frost 10 alarms adapted particularly for giving warning of a dropping in temperature in orchards, and the like, where a freezing or low temperature is harmful and undesirable.

15 An object of the present invention is to provide a device which is thermostatically controlled to close a circuit when the temperature is reduced to a predetermined degree, or thereabouts, for the purpose of 20 operating a bell, a horn, or any suitable electrically controlled mechanism, for taking action when such low temperature is attained.

Various devices of this character have 25 heretofore been patented and commercially produced, but have failed from a practical standpoint in that they are easily broken and subject to tampering with and their adjustment may be easily and accidentally 30 varied or changed to such extent as to render the device unreliable. With the end in view to overcome these disadvantages, the present invention aims at the provision 35 of a frost alarm which has its operation parts housed, sealed and fixed for operation at a predetermined low temperature so that they cannot be tampered with or changed as to the time of operation; which cannot be easily broken; which comprises but few 40 parts so assembled as to produce a device which may be suspended or placed in a desired location where it may be susceptible to slight variations in temperature and unfailingly operate when the temperature 45 falls to a predetermined degree.

A still further object of the invention is to provide a frost alarm of this character which has but one movable part and a pair 50 of contacts, the movable part and contacts being all sealed and enclosed in such manner that access thereto cannot be had, and con-

sequently the fixed relation or adjustment of these parts cannot be accidentally or willfully changed.

With the foregoing and other objects in view 55 the invention will be more fully described hereinafter, and will be more particularly pointed out in the claims appended hereto.

In the drawings, wherein like symbols 60 refer to like or corresponding parts throughout the several views.

Figure 1 is a perspective view of a frost 65 alarm constructed according to the present invention and in one position of use.

Figure 2 is a face view of the device.

Figure 3 is a vertical cross section 70 through the device taken substantially on the line 3—3 of Figure 2.

Figure 4 is a detail perspective view 75 showing a portion of the thermometer tube with one of the contacts blown therein, the section being taken substantially on the line 4—4 of Figure 2.

In the drawings, 10 designates a panel 75 board of any suitable size and configuration for supporting and housing the various parts of the device, the panel board being shown as of rectangular oblong construction in the present instance.

80 A thermometer tube 11, having at its lower end the usual bulb 12 and provided at its upper end with a second bulb 13, is mounted on the panel board 10 and is adapted to extend upwardly at a sufficient 85 inclination to the horizontal to obtain the desired action and at the same time to position the tube 11 substantially longitudinally of the panel board. In the outer face of the panel board 10 a groove 14 is formed 90 of sufficient depth to receive the tube 11 and snugly hold it from vibrating in the panel board, the groove 14 following the configuration of the tube and accomodating the bulbs 12 and 13 at opposite ends.

95 The lower end of the tube 11 is curved downwardly to approach a vertical position and the bulb 12 constitutes the lower termination of the tube. The tube 11 is held in the groove 14 by straps 15 which engage 100 across the outer side of the tube and which are screwed or otherwise suitably secured

to the panel board 10 to hold the thermometer tube 11 firmly in its seat in the panel board. Such construction prevents vibration of the tube so that when the panel board receives jars, falls to the ground, and the like there is little likelihood of the tube 11 becoming damaged.

The bulb 12 is protected by a plate 16 which is secured across the lower end of the 10 groove 14 and over the bulb 12 to ward off impact of surrounding object with the bulb and thus prevent accidental breakage of the same. The plate 12 is preferably slotted or otherwise perforated to admit free 15 access of air to the bulb 12.

The body portion of the tube 11 is also protected and housed by means of a sheath plate or protector 17 which is of sufficient width to overlap the groove 11 and which 20 is laterally enlarged at opposite ends to receive attaching screws 18, or the like, for securing the plate 17 to the face of the panel board 10 and enclose the tube 11. The body portion of the tube 11 may be thus completely enclosed from view and from access 25 by external objects for the complete protection of the tube because the present device is not adapted for adjustment or for taking readings, and the parts thereof are 30 so arranged that they cannot be tampered with and easily broken; thus producing a practical "fool proof" device which cannot easily get out of order.

The tube 11 is adapted to contain a relatively short column of mercury 19, or other suitable electric conducting substance which is arranged intermediately of the body portion of the tube 11 and supported in the tube at opposite ends by columns 20 and 21 of the 40 creosote or alcohol, or other suitably electricity non-conducting substance which is readily susceptible to expansion and contraction under the influence of temperature changes.

45 Blown or otherwise suitably positioned in the tube 11 are fixed contacts 22 and 23 which project into the cavity of the tube in the path of movement of the column of mercury 19, and which are spaced apart 50 a distance which permits simultaneous contact with the mercury only when the latter is permitted to move down in the tube 11 to the desired extent. These contacts 22 and 23 are so located that when a temperature 55 of approximately 34 degrees is reached the column of mercury 19 bridges the contacts and thus closes any electrical circuit in which the contacts may be included. It will be noted that the contacts extend from 60 an inner side of the tube 11, and constitute terminals of wires 24 which are seated in grooves 25 formed in the rear face of the panel board 10. The wires 24 are secured to the inner ends of binding posts 26 which 65 project through the forward face of the

panel board 10, at their inner ends but which are seated in suitable recesses 27 at the inner side of the panel board. The grooves 25 and recesses 27 at the inner side of the panel board may be closed and by 70 suitable covering or layer 28 which is cemented or otherwise secured in position to prevent access to the parts so that such parts cannot be easily broken or disconnected. The outer ends of the binding posts 26 provide 75 terminals for electric wires 29 which lead from a source of electrical energy and to any suitable mechanism as may be desired when a low temperature approaching the freezing point is reached. 80

The device is particularly adapted for use in orchards to protect the trees and fruit from injury from frost, and the device is adapted to be suspended or otherwise placed in an exposed position so that when cold 85 winds or air strike the device it will respond, close the electric circuit and thus operate as desired to protect the fruit.

The panel board 10 may be equipped with a hanger 30 of any suitable construction, 90 and shown in the present instance as in the form of a plate with an inverted key hold slot 31 therein through which a headed nail or the like may be engaged for holding the panel board upon a post, tree, fence or the like, and the plate 30 may be connected to the panel board by a pivot 32 permitting the swinging of the plate 30 downwardly against the rear side of the board out of the way for convenience in storing and ship- 100 ping.

It is obvious that various changes and modifications may be made in the details of construction and design of the above specifically described embodiment of this 105 invention without departing from the spirit thereof, such changes and modifications being restricted only by the scope of the following claims.

What is claimed is:

A thermostatic circuit closer comprising a panel board having an upwardly inclined groove in its outer face extending in a general horizontal direction, a thermometer tube seated in the groove substantially flush with the outer face of the panel board and with its bulb in the lower end thereof, protecting means secured to the outer face of the panel board over the bulb and the tube for housing the same, fixed contacts blown into the lower side of the tube and projecting into the adjacent wall of the groove of the panel board, a non-conducting column of liquid in the lower end of said tube, a column of mercury arranged in the tube, above said non-conducting liquid for bridging said contacts when a predetermined low temperature is reached, said panel board having channels therein leading downwardly from said contacts, wires extending from the con- 110 115 120 125 130

acts downwardly through said channels, binding posts mounted on the outer face of the panel board and terminating at their inner ends in the lower ends of said channels and connected to said wires, the lower end portions of said channels opening through the rear face of the panel board to permit connection of the wires to the binding posts, and a covering plate secured over the rear face of said panel board for **10** housing in the wires and the inner ends of the binding posts.

In testimony whereof I affix my signature.
McCORMACK C. McPHERSON.
